UNITED STATES PATENT OFFICE.

ADELBERT W. R. SCHULTZ, OF CLARION, IOWA.

QUICK-CHANGE PUMP-ROD CONNECTION.

Application filed May 26, 1925, Serial No. 32,945. Renewed April 8, 1927.

This invention relates to couplings for pump rods such as are used to connect windmill pump rods with the sucker rods of ordinary farm pumps.

In the use of farm pumps windmills are frequently employed to drive such pumps, the driving being effected through a long pitman or pump rod extending from the crank shaft of the windmill down through the tower to the pump and coupled at its lower end to the sucker rod of the pump itself. All such pumps are most universally provided with an ordinary hand lever for operating the pump at such times when lack of wind prevents the pump operation by windmill. To use the hand power it is common to disconnect the windmill pump rod from the sucker rod of the pump. Couplings have been devised for this purpose and are frequently in the form of straps and bolts, or at other times they have a socketlike arrangement of one type or other. Straps and bolts, of course, are difficult for a single person to manipulate and any socket arrangement is not only difficult for a single person to use, but even where two people are using the arrangement accidents are apt to occur by the fingers of one of the operators being caught in the socket, owing to the windmill turning over through a little gust of wind or the like.

The important objects of the present invention are to provide a new form of coupling, by means of which a windmill pump rod and the sucker rod of a pump may be quickly connected or disconnected; the connection being effected without the use of tools of any class such as must be used with bolts and nuts; the connection being made by lateral movement and thus being free from the danger of pinching the finger between the ends of the two rods as they move together; and the entire coupling being of such nature as to be readily applied to any ordinary pump and windmill.

With the above and other objects in view the invention consists in general of a novel form of rod coupling having improved arrangement of parts and details, one preferred form of which will now be described and specifically claimed, reference being had to the accompanying drawings, wherein:

Figure 1 is a side view of the lower part of a windmill showing the coupling in use.
Figure 2 is a section on the line 2-2 of Figure 1.

Figure 3 is a face view of the improved coupling with the scale greatly increased over Figure 1.

Figure 4 is a section on the line 4-4 of Figure 3.

Figure 5 is a side view of the device as shown in Figure 3.

Figure 6 is a section on the line 6-6 of Figure 3.

Figure 7 is a section on the line 7-7 of Figure 6.

In the present disclosure there is shown a well casing or top 10 whereon is mounted a pump 11 having the usual pump or sucker rod 12 and being provided with an ordinary pump handle 13 for manual operation when necessary. In the present showing there has also been disclosed a power drive 14 having a pitman 15, the arrangement being that described in my copending application filed of even date herewith, and bearing the Serial Number 32,944, and being here shown for the purpose of illustrating how the present device may be combined with that shown in said copending application. The lower part of the windmill is indicated at 16 and the lower part of the rod at 17. The upper part of the tower and the operating mechanism for the rod 17 are of any well known type and are not deemed necessary here to be shown.

The rod 17 is of the usual form being square in cross section and the rod 12 is also of the usual form, rectangular in cross section. The coupling itself includes a body portion 18 having projecting from one side a pair of parallel flanges 19 between which is received the rod 17, the face of the body portion being provided with teeth 20 to bite into the wooden rod 17. At each side of the body there is provided an elongated eye 21 and these eyes receive the ends of a U-bolt 22 which embraces the rod 17 and clamps the same firmly against the body 18, nuts 23 of the ordinary kind being employed on the threaded legs of the U-bolts. By this means the coupling is firmly fixed to the lower end of the rod 17.

Projecting from the opposite side of the body 18 is a second pair of flanges 24, between which may fit the upper end of the rod 12. The body 18 projects downwardly between the flanges 19, as well shown in Figure 6, and on this downwardly projecting part is supported a pin having a threaded shank 25 which passes through a suit-

able opening in the downwardly projecting end of the body and has on one end a cylindrical head 26 which lies between the flanges 24, its other end being provided with the usual nut 27. Projecting laterally from one of the flanges 24 is a boss or sleeve 28 where-through extends a pivot bolt 29 on which is pivoted one end of a cover plate or keeper plate 30, this plate being of such length as to swing, in closed position, across the channel formed between the flanges 24. On the edge of the flange 24 opposite the boss 28 is a lip 31 notched to receive the bottom edge of the keeper plate 30 upon the latter being moved to said closed position. This keeper plate is preferably arranged so as to cover the end of the pin head 26 when closed and is provided with a knob or handle 32 to enable it to be moved between open and closed positions. The plate is likewise provided with a stop lug 33 for limiting its opening movement.

With this construction the rod 12 is provided with an opening 34 to fit the pin head 26 and in connecting the two rods 17 and 12 the keeper plate 30 is thrown back to dotted line position, as shown in Figure 3 and the pin head 26 slipped into the opening 34. The keeper plate is then moved to the closed or full line position, shown in the same figure and thus the two rods are firmly secured together. Obviously, disconnection may be effected by simply throwing the keeper plate to open position and slipping the pin head 26 out of the opening 34.

Obviously the coupler may be varied in its shape and proportion to suit different shapes or rods and other minor variations may be made as will not effect the scope of the invention. Accordingly it is not desired to confine the invention to the specific form here shown, but it is desired to include all forms as may properly come within the scope claimed.

Having thus described the invention, what is claimed as new, is:

1. A coupling for windmill and pump rods comprising a body portion having a pair of flanges projecting from one face to receive the end of a windmill rod and a second pair of flanges projecting from the other face to receive the upper end of a pump rod, a connecting pin projecting from the last mentioned face between said flanges to engage in an opening in the pump rod, and a keeper plate pivoted to one of the last

mentioned flanges and normally bridging the space between the last mentioned pair of flanges to retain the pump rod between said flanges. 60

2. A coupling for windmill and pump rods comprising a body portion having a pair of flanges projecting from one face to receive the end of a windmill rod and a second pair of flanges projecting from the other face 65 to receive the upper end of a pump rod, a connecting pin projecting from the last mentioned face between said flanges to engage in an opening in the pump rod, a keeper plate pivoted to one of the last mentioned 70 flanges and normally bridging the space between the last mentioned pair of flanges to retain the pump rod between said flanges, and a lip on the second of the last mentioned pair of flanges to support the free 75 end of the plate in bridging position.

3. A coupling for connecting the lower end of a windmill rod to the upper end of a pump rod and comprising a body, means to secure said body on the lower end of the 80 windmill rod, a pair of parallel flanges projecting from the body and forming a vertical channel for the reception of the upper end of the pump rod, a pin projecting from said body between said flanges to engage 85 an opening in the pump rod, a keeper plate pivoted to one flange and swingable to engage against the other flange and bridge the space between said flanges, and means to retain the keeper plate in bridging position. 90

4. A coupling for connecting the lower end of a windmill rod to the upper end of a pump rod and comprising a body, means to secure said body on the lower end of the windmill rod, a pair of parallel flanges projecting from the body and forming a vertical channel for the reception of the upper end of the pump rod, a pin projecting from said body between said channels to engage an opening in the pump rod, a boss on the outer 100 side of one of said flanges, a pivot bolt supported in said boss parallel to said flange, a keeper plate having one end mounted on said pivot bolt to swing over the space between the flanges and thereby bridge the 105 open side of the channel to hold the pump rod on said pin, and a lip projecting from the remaining flange and engage the free end of the plate and support the plate in bridging position. 110

In testimony whereof I affix my signature.

ADELBERT W. R. SCHULTZ.
